STEEL WOOL PACKAGE

Alvin G. Bowe, Chicago, Ill., assignor to James H. Rhodes & Company, Chicago, Ill., a corporation of Illinois

Filed July 20, 1959, Ser. No. 56,865

Term of patent 14 years

(Cl. D58—12)

Fig. 2

FIG. 1 is a top perspective view of a steel wool package embodying my new design; and

FIG. 2 is a top plan view of the package shown in FIG. 1.

The dominant features of my design reside in the portions shown in full lines.

I claim:

The ornamental design for a steel wool package, as shown and described.
